US0D1102384S

(12) **United States Design Patent** (10) Patent No.: **US D1,102,384 S**
(45) Date of Patent: ** Nov. 18, 2025

(54) **PART OF AN OPTICAL FIBER CONNECTOR**

(71) Applicant: **ACON OPTICS COMMUNICATIONS INC.**, New Taipei (TW)

(72) Inventors: **Jia-Rong Wu**, New Taipei (TW); **Tsung-Yao Hsu**, New Taipei (TW)

(73) Assignee: **ACON OPTICS COMMUNICATIONS INC.**, New Taipei (TW)

(**) Term: **15 Years**

(21) Appl. No.: **29/917,805**

(22) Filed: **Nov. 22, 2023**

(30) **Foreign Application Priority Data**

Sep. 8, 2023 (TW) 112304644

(51) **LOC (15) Cl.** **13-03**

(52) **U.S. Cl.**

USPC **D13/133; D13/147**

(57) **CLAIM**

The ornamental design for a part of an optical fiber connector as shown and described.

DESCRIPTION

FIG. 1 is a perspective view of a part of an optical fiber connector showing my design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.
